UNITED STATES PATENT OFFICE.

PATRICK R. BANNON AND JAMES L. BANNON, OF JOLIET, ILLINOIS.

SELF-DUMPING CAR.

No. 805,517.

Specification of Letters Patent.

Patented Nov. 28, 1905.

Application filed November 27, 1903. Serial No. 182,875.

To all whom it may concern:

Be it known that we, PATRICK R. BANNON and JAMES L. BANNON, citizens of the United States, residing at Joliet, in the county of Will and State of Illinois, have invented certain new and useful Improvements in Self-Dumping Cars, of which the following is a specification.

This invention relates to means for constructing railroad road-beds of dirt, stone, &c., or for conveying and dumping such material to form a roadway for any purpose; and it consists generally of a series or train of self-dumping cars which are coupled together, provided with suitable trucks, and constructed with bottoms and sides formed of short sections flexibly coupled together to form an endless conveyer, which is adapted to travel over suitable pulleys, wheels, guides, or other supports and to convey the filling material to the rear end of the train, where it is automatically dumped upon the road-bed under construction.

The especial objects attained by our invention are the conveying of the filling material commonly used in the construction of road-beds from the source of supply to the point where it is required and the dumping of such material directly on the road-bed, whereby much of the grading now done by hand-shovels is saved.

A further object is to provide means whereby the entire train-load of filling material may be conveyed to the end of a track laid to the edge of a gully, ravine, marsh, &c., and dumped at such point, thus providing a "fill" or foundation upon which the track may be extended, and the operation repeated until the work is completed, thus avoiding the erection of trestles or the use of "false" work, the frequent laying and raising of temporary or construction track, and other expensive expedients.

An additional object is to provide carrying means that may be loaded or filled at the top in any well-known manner and, if desired, may be unloaded at the sides with shovels in the usual way instead of automatically at one end of the train as especially provided by our invention.

A further object is to secure a conveying and dumping device that may be easily moved over a track from a point of supply of the filling material to the place where such material is to be utilized.

In this application for patent we have shown our invention as applied to cars adapted to travel over railway-rails; but it will be apparent that the same principles may be utilized in connection with trucks mounted on traction-wheels. It will also be plain that the supporting-beams, which constitute the frame on which the conveyer travels, will permit of varied treatment as to size, material, shape, and arrangement, all within the scope of the essential features of our invention. We therefore do not wish to be understood as confining our invention to the exact construction and arrangement shown herein, but intend that this application shall be a preferred exemplification of the principles of our invention.

In the accompanying drawings we have shown our invention in a series of views, of which—

Figure 1 shows in side elevation three cars constructed according to our invention combined with an engine of an ordinary form for transmitting motion to the conveyer which constitutes the car-floor. Fig. 2 is a top plan view of the cars shown in Fig. 1. Fig. 3 is a longitudinal section of one car and the end of the adjacent car constructed according to our invention and on a larger scale than Figs. 1 and 2. Fig. 4 is a cross-section on the lines 4-4 of Fig. 3. Fig. 5 is a detail showing the rod-and-pinion gearing which is utilized in our invention as a feature of the driving means. Fig. 6 is a detail in plan, on an enlarged scale, of a portion of the driving devices which are secured to the under side of the car-floors and which, with the rod-and-pinion gearing and intermeshing sprocket-wheels, cause the travel of the car-sections. Fig. 7 is a detail showing the method of supporting the car-floor at the dumping end of the train.

Referring to the details of the drawings, 8 represents the cross-sills of the car-frame, which are suitably supported on axles and wheels and to which are bolted the uprights 8^a and the longitudinal sills 8^b. Connected to the uprights about midway their top and bottom are transverse iron beams 8^c, and at the upper ends of the uprights are channel-beams 8^d, which extend longitudinally with the frame and serve as guides for the sides of the car-floor. Supported on the cross-sill beams 8 are I-beams 9, which extend longitudinally of the car and furnish a support for the L- 110

bars 9^a, in which are suitable bearings for the shafts, on which are mounted the series of grooved rollers 10. Secured to the upper flanges of the cross-beams 8^c are short lengths 5 of I-beams 11, to the upper flanges of which are bolted L-bars 11^a, in which are bearings for the shafts of the grooved rollers 12.

To make the frame rigid and strong and provide bearings for shafts to be described, 10 there are bolted to the beams 11 wooden beams 13, which extend longitudinally of the car and have bolted to them the upper portions of uprights 8^a. Secured to the center of the cross-sills 8 are coupling-heads 14, 15 which may be of any desired pattern and have adapted thereto any suitable form of coupling whereby two cars may be flexibly secured together. Supported on the under side of the midway beams 8^c are pillow-blocks 15, which 20 provide bearings for the shafting 18^b, by which power is transmitted from one car to the other. The car-bodies are of the general gondola form; but the floors are constructed from plank in short sections 16, near the ends 25 of which are suitably secured the iron plates 17^c, which form the sides of the car and correspond in width to the floor-sections. Bolted to the under side of each car-floor section are short rails 16^a, the downwardly-depending 30 web of which fits the grooved periphery of the rollers 12, thus forming guides and supports for the floor-sections which are loaded. To the upper sides of the floor-sections are bolted rails 16^b, corresponding to the length 35 of such section, the web of which fits the grooved face of the rollers 10, which thus support the sections of the floors that have been unloaded. To the under side of the car-floor and along the center of same are bolted 40 plates 17, each of which is formed with rounded teeth 17^a along its sides, with a pair of lugs 17^b at one end and a single lug 17^c at the opposite end, and said lugs have openings therethrough for coupling-pins. The lugs 17^b 45 of one plate are coupled to the single lug 17^c of the adjacent plate by the coupling-pin 17^d, as clearly shown in Fig. 6. It will be understood that each of these plates corresponds in length to the length of one of the floor-sections, 50 so that the coupling-point is at the edge of each section. The plates 17 constitute a series of links in an endless belt, through which power is applied to the under side of the floor of the car-sections from 55 sprocket-wheels, which mesh with the teeth of the plates. The floor-sections are also secured together by hinges 17^e, as shown in Fig. 4.

Extending transversely of the cars, near the 60 ends thereof, and mounted in suitable bearings in the frame are shafts 18, on which are mounted sprocket-wheels 19 and beveled pinions 20. Arranged between the oppositely-placed beveled pinions 20 are smaller beveled pinions 18^a, which are fixed on the opposite

ends of the shafts 18^b. It will be noted, as shown in Fig. 5, that the pinion 18^a on one end of the shaft 18^b of one car meshes with only one of the adjacent beveled pinions 20, thus transmitting motion thereto and driving 70 the transverse shaft 18, on which said pinion 20 is mounted, whereby the opposite pinion 20 on the same shaft 18 is driven and communicates its power to the beveled pinion 18^a on the shaft 18^b on the next car in the train, thus 75 transmitting power from one car to the other. The sprocket-wheels 19 are so spaced on the shaft 18 as to engage the teeth 17^a of the plates 17, thus causing the floor-sections to traverse the length of each car and of the 80 whole train. At the outer ends of the first and last cars of a train composed of cars constructed as above described are mounted drums 85 20^a, having six flat sides which correspond in length to the length of the floor-sections and furnish supports for such sections when they turn to dump their contents at the unloading end of the train and when they return from their inverted or dumped to their upright position at the front end of the train, as shown 90 in Fig. 1. These drums are mounted on the shafts 18, that carry the sprocket-wheels 19, and are arranged on opposite sides of such wheels and also near the ends of the shafts, so as to furnish a support for the floor-sections 95 at the center and near the ends of the latter. The engine 21, mounted on the separate car 21^a, may be of any desired construction and is used to drive the shaft 22, which in turn, 100 through suitable intermeshing beveled gears, drives the shafts 23, carrying beveled pinions which intermesh with the beveled wheels 20 on the ends of a shaft 18, suitably mounted at the end of the train. It will be understood that the gears 20 and the shaft 18 and shaft 105 23, with its pinions, will be arranged on both end cars of the train, so that an engine for driving the conveyer may be applied at either end, as may be most convenient. It will be also understood that a train made up of cars 110 of the character described will be hauled over a railroad-track by any suitable locomotive, which will be coupled to the train at the end opposite the dumping-car.

In operation a train of cars embodying the 115 features above set forth may be filled at the top by any suitable loading apparatus, the cars being moved past the loading-point as fast as they are filled. When all the cars are full, the train will be pushed rear end first by 120 a locomotive to the place on the road-bed to be filled, when the rear or dumping car will be run out as far as the road-bed will permit, whereupon the engine 21 will be started, thus moving the conveyer-sections of the loaded 125 cars toward the rear end of the train, where as the sections turn about the drum on the outer end of the last car the material will be dumped directly on the right of way or road-bed under construction. When the bed has 130

been filled to the desired grade at one point, new rails will be added at the end of the track to permit the continuation or extension of the filling operations as before until the work is completed.

We have not shown in detail the construction and arrangement of the driving means for the car or conveyer sections, because it is manifest that various methods may be adopted for applying power to such sections to cause them to traverse a train.

Having thus described our invention, what we claim, and desire to obtain by Letters Patent, is—

15 1. In mechanism of the class described, cars provided with suitable trucks and coupled together to form a train each of said cars provided with sectional and movable sides and floor, the floor composed of a series of sections hinged to each other, and the floor of one car connected with the floor of the adjacent car.

2. In mechanism of the class described, cars provided with suitable trucks and coupled together to form a train, each of said cars provided with a floor composed of a plurality of movable sections each consisting of a bottom plate and side walls, said sections hinged together to form an endless belt extending the length of said train, means for causing said sections to traverse said train, and means for supporting said sections when loaded and when unloaded.

3. In mechanism of the class described, a train composed of a series of cars, each of which is provided with movable and sectional sides and bottom connected to form an endless belt extending the length of the train and the end cars of the train also provided with rotatable drums over which said endless belt travels, and means for driving said belt.

4. In mechanism of the class described, a series of cars coupled together to form a train, each of said cars composed of a rigid supporting-frame and movable and sectional sides and bottom, the sides and bottom of each car being flexibly connected to the corresponding portions of the adjacent cars, means secured to said frame for supporting the said sectional bottoms, means for guiding the same when in

motion and means for transmitting motion to said sides and bottom.

5. In mechanism of the class described, a series of cars flexibly coupled together to form a train, each car consisting of longitudinal and transverse beams joined together to form a rigid frame, and of sides and bottom composed of a plurality of short sections extending the full width of the car, said sections flexibly connected together, toothed plates secured to the under side of the floor-sections, toothed wheels mounted on said frame and engaging the teeth of said plates, and means for driving said toothed wheels.

6. In mechanism of the class described, cars coupled together to form a train, each car consisting of a suitable frame mounted on trucks, and of sides and bottom formed in sections flexibly connected together, and the sections composing the floor of one car flexibly connected with the corresponding sections of the adjacent floor so as to form a continuous belt, and means for causing said sections to traverse the length of the train consisting of toothed plates secured to the bottom of the floor-sections, of toothed wheels engaging the teeth of said plates and mounted on shafts extending transversely of said cars, and means for transmitting motion to said shafts consisting of drive-rods and intermeshing gears, substantially as described.

7. In a train of the class described, a series of intermediate cars each composed of a frame supported on a truck, of mobile floor and sides formed in sections and the floor-sections flexibly connected together, end cars coupled with the intermediate cars and composed of a frame of mobile floor and sides formed in sections and the floor-sections coupled together and to the corresponding sections of the intermediate cars, and means mounted on the end cars for supporting the sections at their turning-points.

In testimony whereof we affix our signatures in presence of two witnesses.
